(57) **CLAIM**

The ornamental design for a foldable game board with fastener for Chinese checkers, as shown and described.

DESCRIPTION

FIG. 1 is a perspective view showing the foldable game board with fastener for Chinese checkers in a folded configuration embodying my new design;

FIG. 2 is a perspective view showing the foldable game board with fastener for Chinese checkers in an open configuration showing the interior wall surface embodying my new design;

FIG. 3 is a perspective view showing the foldable game board with fastener for Chinese checkers in an open configuration showing the exterior wall surface embodying my new design;

FIG. 4 is a front view of the closed configuration thereof;

FIG. 5 is a back view of the closed configuration thereof;

FIG. 6 is a side view of the closed configuration thereof, the other side view being a mirror image thereof;

FIG. 7 is an end view of the closed configuration thereof, the others end view being a mirror image thereof;

FIG. 8 is a front view of the open configuration thereof;

FIG. 9 is a back view of the open configuration thereof;

FIG. 10 is a side view of the open configuration thereof, the other side view being a mirror image thereof; and,

FIG. 11 is an end view of the open configuration thereof, the end view being a mirror image thereof.
